UNITED STATES PATENT OFFICE.

CHARLES S. WRIGHT, OF WEST STOUGHTON, MASSACHUSETTS.

SHUTTLE.

1,394,878.

Specification of Letters Patent. Patented Oct. 25, 1921.

Application filed December 18, 1920. Serial No. 431,734.

To all whom it may concern:

Be it known that I, CHARLES S. WRIGHT, a citizen of the United States, residing at West Stoughton, county of Norfolk, State 5 of Massachusetts, have invented an Improvement in Shuttles, of which the following description, in connection with the accompanying drawing, is a specification, like characters on the drawing representing like 10 parts.

This invention relates to shuttles of that type used in automatic weft-replenishing looms wherein the replenishment of weft is effected by discharging the spent bobbin 15 from the shuttle and substituting a fresh bobbin therefor. The invention has particular reference to the holding spring employed in the shuttle for holding the bobbin in the shuttle. In this type of loom the 20 change of the bobbin in the shuttle is effected by means of a so-called transferrer which operates upon exhaustion of the weft to drive a filled bobbin out of a hopper into the shuttle, and by this act to engage the 25 spent bobbin in the shuttle and force the latter down through the open bottom of the shuttle. The bobbins are held in place in the shuttle by means of rings on the heels of the bobbins which engage notches formed 30 in the holding spring, and in order to insure that the bobbin is properly placed in the shuttle, it is necessary for the transferrer to follow the bobbin in its transferring movement to a point where the bobbin is 35 correctly held by the spring jaws. This involves the movement of the transferrer somewhat into the bobbin-receiving space in the shuttle. Furthermore, in order that the transferrer may have this extent of movement, it is necessary that the shuttle should 40 be properly positioned during the transferring operation for if the shuttle is late in its entry into the shuttle box, there is danger that the transferrer will strike the shuttle and injure the latter. One of the objects 45 of my invention is to provide an improved bobbin-holding spring which not only functions to hold the bobbin properly positioned 50 after it has been transferred to the shuttle, but which also acts to complete the transferring movement of the incoming bobbin, thus relieving the transferrer of some work. With my improved spring it is sufficient if 55 the transferrer carries the bobbin down to a point where it is entered between the jaws

of the spring, for after the bobbin has once been entered the spring acts to complete the movement of the bobbin and carry it home. Hence with my invention it is not necessary to give the transferrer as great an extent of 60 movement as has heretofore been thought necessary. This allows me to have the movement of the transferrer occur at a later period than would otherwise be necessary, and thus a bobbin can be transferred 65 into a "late" shuttle without danger of injury.

Furthermore, less power is required to operate the transferrer where my invention is employed than is the case where the transferrer has to make the full extent of movement above referred to.

Other advantages are derived from using my invention which will be more fully herein-after set forth.

In order to give an understanding of my invention, I have illustrated in the drawings a selected embodiment thereof which will now be described, after which the novel features will be pointed out in the appended 80 claims.

Figure 1 is a plan view of a portion of a shuttle having a shuttle spring embodying my invention;

Fig. 2 is a section on the line 2—2, Fig. 85 1, showing the bobbin in position;

Fig. 3 is a section also on the line 2—2, Fig. 1, showing the operation of placing a fresh bobbin in the shuttle equipped with my invention;

Fig. 4 is a view of one of the jaws of the 90 spring;

Fig. 5 is a section on the line 6—6, Fig. 1.

In the drawings, 1 indicates a portion of a shuttle body having the usual bobbin-receiving slot or opening 2 formed therein, and 3 indicates a bobbin in the shuttle which is formed with the butt or heel end 5 that is received in the holding spring, said heel of the bobbin having the usual metal rings 100 4 encircling the same.

My improved bobbin-holding spring is of the usual forked type, it having the two resilient arms 6 between which the heel of the bobbin is received, said arms having notches 105 7 formed therein to receive the rings 4 on the bobbin.

In order to obtain a better understanding of the invention, it may be helpful at this time to refer to the action of the ordinary 110

holding spring when a bobbin is being transferred into the shuttle. This is illustrated in Fig. 5 wherein the arms of the holding spring are indicated at 8. 9 indicates the transferrer which is constructed to move downwardly toward the shuttle during the change of bobbin and which operates to take a bobbin from the hopper and carry it into the shuttle and force the heel 10 of the bobbin between the arms 8 of the holding spring. The entrance of the filled bobbin into the shuttle will eject the spent bobbin. In order to insure that the filled bobbin is properly positioned in the spring 15 it has heretofore been necessary to give the transferrer a movement sufficient to place the filled bobbin completely in the bobbin-holding spring. If the movement of the transferrer stops short of this movement 20 with the bobbin only partly entered between the arms of the spring, there is danger that the bobbin will snap out of the spring when the transferrer retreats. The carrying of the transferrer clear into the shuttle, requires that the shuttle should be properly positioned during the transferring operation, for if when a change of bobbins is to take place the shuttle is slow in being boxed, or is what is commonly termed a "late" 25 shuttle, the transferrer will carry the filled bobbin against the end of the shuttle instead of into the bobbin-receiving space in the shuttle thereby causing more or less damage.

30 As stated above, my improved bobbin-holding spring is constructed so that it has a positive action on the bobbin in forcing the latter home, so that the transferrer may be relieved of that much work.

35 The arms 6 of my bobbin-holding spring are made of increased width, as shown in Figs. 2, 3 and 4, so that there is a considerable space between the notches 7 and the top of each arm. The upper portion of the inner face of each arm is curved inwardly slightly, as shown at 10, and the upper edge of each arm is beveled, as shown at 11. This forms a ridge or shoulder 12 on the inner face of each arm adjacent the upper edge. 40 Each arm is also extended below the notches 7, as shown at 13, and the extended portion 13 is curved inwardly slightly, as best seen in Figs. 2 and 3. The vertical dimensions of each arm 6 at the notched portion thereof is such 45 that when a fresh bobbin is being placed in the shuttle the spent bobbin will not be carried out from between the arms 6 until the center of the incoming bobbin has been carried below the ridges or shoulders 12, as seen 50 in Fig. 3. After the incoming bobbin has reached the position shown in Fig. 3 and the ridges or shoulders 12 are situated above the 55 horizontal diameter, the resiliency of the spring will have the effect of forcing the 60 incoming bobbin down into the position 65

shown in Fig. 2. This is because the pressure of the springs against the rings 4 due to the resiliency of the springs forces the ridges or shoulders 12 against the rings above the center of the bobbin. With my 70 invention, therefore, it is sufficient if the transferrer 9 carries the incoming bobbin to the point shown in Fig. 3, and then leaves it, for after the shoulders 12 have been carried above the horizontal diameter of the 75 bobbin, then the spring will act to prevent the bobbin from jumping out from the shuttle and will serve to force the bobbin downwardly into its proper position. It will thus be obvious that with my invention the 80 transferrer may have a considerable less extent of movement than with other bobbin-holding springs as now commonly used without danger that the bobbin will fail to be carried home. An advantage which results from this construction is that it is possible to delay the action of the transferrer somewhat, for since it does not have to make a movement of so great an extent as heretofore, it is possible to have the transferrer 85 commence its movement a little later. This will accommodate any "late" shuttle and will yet insure that the transfer of the bobbin is properly effected. Another advantage which is inherent in this construction is that 90 the movement of the transferrer in transferring a bobbin from the hopper to the shuttle does not tend to draw the bobbin against the side of the shuttle because of the fact that the downward or transferring motion 100 of the transferrer terminates at about the position shown in Fig. 3. This transferrer has an oscillating movement about a center and at the time it reaches the point shown in Fig. 3, the face of the transferrer which 105 is against the bobbin is about on the horizontal line of the center. Any motion of the transferrer below this horizontal line would carry the face slightly toward the shuttle due to the arc-shaped path in which the face 110 moves, but because the transferrer terminates its motion on the horizontal line of the center or motion there is no tendency to swing the bobbin inwardly toward the side 115 of the shuttle.

It will be noted that in my invention the upper edges of the widened portions of the arms 6 are situated just below the top face of the shuttle so that as soon as the bobbin has entered the shuttle to the extent shown 120 in Fig. 3 said bobbin is in position to be forced home by the resiliency of the spring arms. It will also be noted that the distance between the upper and lower edges of the widened portion of the spring arms is at 125 least as great as the diameter of the heel of the bobbin.

15 indicates the usual guide member which is employed to assist in guiding the bobbin into the jaws of the bobbin-holding spring. 130

In my invention I make this guide with the curved portion 16 instead of with a straight angular portion as is usually done, I find that with such a curved portion the bobbin 5 is guided into position with an easier movement.

I claim:

1. A shuttle having a bobbin-receiving recess and a forked bobbin-holding spring, the 10 arms of the spring having relatively wide ends, the upper edges whereof are only slightly below the top of the shuttle, said arms being provided with notches to receive the rings on the bobbin heel and being 15 curved inwardly from the notches to the upper edges, each arm having a beveled top edge which forms with the inward curvature a ridge or shoulder closely adjacent the top edge of the arm whereby when a bobbin has 20 been carried into a shuttle sufficiently so that the horizontal diameter of the heel is below the shoulder or ridge, the resiliency of the spring arms together with the curvature

thereof will force the bobbin heel into the notches.

2. A shuttle having a bobbin-receiving recess and a forked bobbin-holding spring, the upper edges of the arms of the spring being only slightly below the top of the shuttle, each arm of the forked spring having a relatively wide end provided with notches to receive the rings on the bobbin heel, the portions of each arm above and below the notches being curved inwardly and each arm having on its inner face adjacent its top 30 edge a ridge or shoulder which is located from the bottom edge of said wide end a distance at least as great as the diameter of the heel of the bobbin, whereby a bobbin being introduced into the shuttle will have its 35 horizontal diameter carried below the ridges before the spent bobbin has been ejected from the shuttle.

In testimony whereof I have signed my name to this specification.

CHARLES S. WRIGHT.
